CATHODE-RAY BEAM DEFLECTION SYSTEM

William J. Stolze, Astoria, Long Island, and Earl I. Anderson, Manhasset, N. Y., assignors to Radio Corporation of America, a corporation of Delaware

Application October 28, 1947, Serial No. 782,490

7 Claims. (Cl. 315—29)

1

The present invention relates to cathode ray beam deflection systems, and more particularly relates to systems of this nature in which at least one direction of deflection of the cathode ray beam is carried out through the action of an electrostatic field.

It is known in the art that negative feedback may be employed in connection with amplifier circuits in order to reduce distortion of the output waveform. This is usually accomplished by taking a portion of the voltage output of the amplifier and applying this portion of the output voltage to the amplifier input in such a manner that its phase is negative. Thus any distortion introduced between the points bridged by the feedback connection is decreased in magnitude.

A system such as the above is satisfactory in many cases, but has the disadvantage that the gain of the amplifier is reduced to an appreciable extent. It has been found, however, that this loss in amplification may be cut down, and at the same time an improvement may be obtained in waveform fidelity, by the provision of a separate network connected to the output of the amplifier but preceding the network causing the distortion. This separate network is specifically designed to produce the same type of distortion present in the output of the system, but to an even greater degree. If the voltage output of this separate wave-shaping network is then applied to the input of the amplifier proper, the resulting output of the system more closely resembles the input waveform than in cases where the usual feedback arrangement is used.

The above concept has been utilized, in one embodiment of the present invention, in connection with a cathode ray beam deflection circuit of the electrostatic type. One of the requirements for the vertical, or field, deflection circuit of a television receiver employing an electrostatically deflected cathode ray tube is that the condensers for coupling the vertical deflection amplifier to the cathode ray tube deflection plates must be normally of fairly large capacitance due to the relatively low frequency of vertical deflection. Furthermore, these condensers must have a high voltage rating due to the fact that the vertical deflection plates of the cathode ray tube are usually maintained at or near the full second anode potential of the cathode ray tube in order to prevent a defocusing of the cathode ray scanning beam which may result if the deflection plates are operated at a substantially lower potential than exists on the tube accelerating electrode. As a consequence, not only are these

2

coupling condensers large in a physical sense, but in addition they are relatively expensive and tend to increase materially the total cost of the television receiver.

By using the principle of the present invention, it has been found that both the size and cost of the above-mentioned coupling condensers may be considerably reduced. It will be appreciated that the normal effect of reducing the capacitance of each coupling condenser is to introduce distortion into the waveform of the voltage applied to the deflection plates of the cathode ray tube, since the time constant of the coupling circuit is not high enough to pass the sawtooth voltage generated by the power output tubes in its undistorted form. The resulting non-linearity of vertical deflection results in a poor television image and hence is highly undesirable.

By the use of the present invention, however, a portion of the sawtooth voltage output from the power tube (or from one to two push-pull operated power tubes) is applied to a separate wave-shaping network. This separate network is designed to produce in the sawtooth wave a type of non-linearity similar to that produced by the relatively small capacitance of the coupling condenser, but to an even greater degree. The highly distorted voltage thus obtained from this separate network is fed back in proper phase to the input of the power tube, so that the output of the latter is no longer of sawtooth wave-form, but instead contains distortion in opposite phase to the distortion produced by the coupling condenser. Hence, after passing through the coupling condenser, the two types of distortion in effect cancel one another, and the resulting voltage wave as applied to the vertical deflection plates of the cathode ray tube is substantially a pure sawtooth which is effective to bring about a linear deflection of the cathode ray scanning beam.

One object of the present invention, therefore, is to provide an improved type of vertical, or field, deflection system for use with electrostatically deflected image-reproducing cathode ray tubes.

Another object of the invention is to provide an improved cathode ray beam deflection system of the electrostatic type in which improved linearity of deflection is obtained through the use of a separate wave-shaping network, the output of which is applied to the deflection system to reduce distortion resulting from the employment of less bulky and more economical circuit components.

A still further object of the present invention is to provide, in a cathode ray beam deflection circuit of the electrostatic type wherein the normal sawtooth voltage output of a push-pull amplifier is applied to the field deflection plates of a cathode ray tube and which voltage is then distorted by the use of coupling condensers of small capacity resulting in a time constant which is inadequate for the frequency of field deflection of the cathode ray scanning beam of the cathode ray tube, a separate wave-shaping network designed to distort a portion of the output voltage of the amplifier to an even greater degree than that produced by the coupling condensers, and further means for applying the output of this wave-shaping network to the input of the push-pull amplifier with such magnitude and phase as to substantially cancel on the deflecting plates the distortion produced by the presence of the coupling condensers.

Other objects and advantages will be apparent from the following description of a preferred form of the invention and from the drawings, in which:

Fig. 1 is a circuit diagram of a preferred embodiment of the present invention; and

Fig. 2 is a set of voltage waveforms illustrating the operation of the circuit of Fig. 1.

Referring now to the drawings, there is shown an image-producing cathode ray tube generally indicated by the reference numeral 10. Tube 10 may be an electrostatically deflected cathode ray tube of any suitable type which includes a pair of vertical, or field, deflection plates 12 and 14. Although tube 10 is also assumed to include a pair of horizontal, or line, deflection plates, these have not been shown in order to simplify the drawing, inasmuch as the explanation is based on application of the principle to the vertical plates. It is further assumed that a beam of electrons is developed and directed toward the cathode ray tube screen 16 by an electron gun 18 in the customary manner. A second anode 20 (which may be in part a conductive coating on a portion of the inner surface of tube 10) accelerates the electrons emitted from the electron gun 18 toward the luminescent screen 16.

A pair of vertical, or field, power output tubes, illustrated as two triodes 22 and 24, may actually comprise separate tubes or they may constitute the two sections of a twin triode (such as a 6SN7GT) having a common envelope. Tube 22 is provided with an anode 26, a cathode 28, and a control electrode or grid 30. Tube 24 is similarly provided with an anode 32, a cathode 34, and a control electrode or grid 36. The joined cathodes 28 and 34 of tubes 22 and 24 respectively are connected through a common cathode resistor 37 to the grounded negative terminal 38 of the source of operating potential for the power output tubes, designated as B+ in the drawing.

Anode 26 of tube 22 is connected to the positive terminal 40 of the source of tube operating potential through the load resistor 42. Anode 32 of tube 24 is likewise connected to the same positive terminal 40 through another load resistor 44 which preferably is of the same value as resistor 42. A charging condenser 46 has one of its plates connected and its other plate connected to the positive supply voltage source terminal 48 through two series-connected resistors 50 and 52, the former being adjustable in order to vary the positive charge developed on condenser 46. A vertical discharge tube 54 is effectively connected in shunt with the condenser 46, and is

arranged to periodically discharge the condenser 46 so that the voltage developed thereon (and as applied to the grid 30 of tube 22) will be of substantially sawtooth waveform, in a manner well known in the art.

The vertical power tubes 22 and 24 are arranged to operate in push-pull relation by means of a sawtooth voltage applied to grid 36 of tube 24 which is 180° out-of-phase with the sawtooth voltage appearing on grid 30 of tube 22. This out-of-phase voltage is obtained by the use of two resistors 56 and 58 connected in series between ground and the anode 26 of tube 22. These resistors 56 and 58 act in effect as a voltage divider to produce a sawtooth wave of desired amplitude on grid 36, and, due to the phase-inversion properties of tube 22, this voltage on grid 36 will be such as to cause the tubes 22 and 24 to operate in the required push-pull manner.

The sawtooth voltage normally appearing on anode 26 of tube 22 is applied to the vertical deflecting plate 12 of the cathode ray tube 10 through a coupling condenser 60. Similarly, the sawtooth voltage normally appearing on anode 32 of tube 24 is applied to the vertical deflecting plate 14 through a coupling condenser 62. In order that the operating potential of the deflecting plates 12 and 14 be at or near the potential applied to the second anode 20 of the cathode ray tube and thus preclude a defocusing of the cathode ray beam developed by the electron gun 18, the deflecting plates 12 and 14 are connected to the high-voltage source (H. V.) of the system through two resistors 64 and 66, respectively.

It has been found in practice that a deflection of the cathode ray scanning beam of tube 10 at the usual vertical, or field, frequency of 60 cycles per second requires that the coupling condensers 60 and 62 be of relatively large capacitance in order accurately to pass the sawtooth voltage wave normally produced by the push-pull amplifier 22-24. In order that the time constant of the RC networks 60-64 and 62-66 be sufficiently high, therefore, the condensers 60 and 62 should preferably be in the order of .05 microfarad. The use of condensers having such a rating is undesirable, however, since they are quite large in a physical sense and also of fairly high cost. It has not been practicable, heretofore, to reduce their size in previously used deflection systems, since to do so in previously used systems would result in considerable distortion of the sawtooth output of the push-pull amplifier as it appears on the cathode ray tube deflecting plates.

In accordance with one embodiment of the present invention, the capacitance of the condensers 60 and 62 may be reduced to a small fraction of the size normally required, and at the same time any distortion which would normally result from such an act is overcome. The means for accomplishing this result comprises a separate wave-shaping network connected to receive a portion of the normal sawtooth voltage output of tube 22 as it appears on anode 26. This wave-shaping network includes a condenser 68, one plate of which is connected to the anode 20 of tube 22 and the other plate of which is connected to one end of a resistor 70. The remaining end of resistor 70 is connected to the grounded negative terminal of the operating potential source. Thus, if the time constant of the RC network 68-70 is made equal to or shorter than the time constant of the RC networks 60-64 and 62-66, then the voltage appearing between condenser 68 and resistor 70 will include a distortion

similar to that appearing on the deflecting plates 12 and 14, as shown in Fig. 2. In fact, the distortion may be made even more pronounced, according to the values chosen for condenser 68 and resistor 70.

The intentionally distorted output of the wave-shaping network 68-70 is applied through an additional condenser 72 to the grid 30 of the vertical power tube 22, and, since the voltage applied to the wave-shaping network 68-70 is derived from the output of tube 22, it follows that the voltage thus fed back through condenser 72 (see Fig. 2) will be of such phase as to cancel in the voltage waveform appearing on deflecting plate 12, the distortion produced by what normally would be an inadequate capacitance rating for the coupling condenser 60.

From the above, it will be seen that the only additional components required in the circuit of Fig. 1 in order to overcome the non-linearity produced by the use of a reduced capacitance for the coupling condensers 60 and 62 are the two condensers 68 and 72 and the resistor 70. If the condenser 68 is chosen to have a value of .0015 microfarad, for example, and the resistor 70 is chosen to have a value of 2.8 megohms, then it is possible to reduce the value of each of the coupling condensers 60 and 62 from their standard rating of .05 microfarad to a lower rating of .005 microfarad, or, in other words, the capacitance of each may be reduced to 10% of its lower value. Condensers of the latter rating are of course, much less bulky and expensive. A corresponding ten-fold increase in the values of resistances 64 and 66, to retain the original time constant, would obviously be impractical. The present invention makes it possible to materially reduce the size of the coupling condensers 60 and 62 and still obtain the desired linearity of deflection even though the time constant of the elements in the deflection circuit is materially and correspondingly decreased.

The two condensers 72 and 46 are connected effectively in series between ground and the output of the wave-shaping network 68-70. Therefore, the ratio between the values of condensers 72 and 46 determines the percentage of the voltage output of network 68-70 which is fed back to the grid 30 of tube 22.

While the above description has assumed a cathode ray beam deflection system using a pair of power output tubes arranged in push-pull relation, nevertheless it will be apparent that applicants' invention is equally applicable to a deflection system of the so-called "single-ended" type in which but a single power output tube is employed.

While normally the ratings of the components 68, 70 and 72 are chosen so that the amount and degree of distortion fed back to the power tube 22 is just sufficient to cancel the distortion introduced by the low-value coupling condensers 60 and 62, it will be appreciated that an even greater degree of distortion may be produced by the wave-shaping network so as to over-compensate for the effect of condensers 60 and 62 if and when such a result is desirable.

Having thus described our invention, we claim:

1. In a cathode ray beam deflection circuit of the electrostatic type, wherein the normal sawtooth voltage output of a push-pull amplifier as applied to the field deflection plates of a cathode ray tube is distorted by the use of coupling condensers of small capacity relative to the fre-

quency of field deflection of the cathode ray scanning beam of said cathode ray tube, the combination of a wave-shaping network, a circuit for applying a portion of the normal sawtooth voltage output of said amplifier to said wave-shaping network to thereby produce in the sawtooth voltage output from said network a degree of distortion at least as great as that which normally appears on the said deflecting plates due to the relatively small capacity of said coupling condensers, and a further circuit for applying the distorted sawtooth voltage output from said wave-shaping network to the input of said push-pull amplifier, the distorted sawtooth voltage thus fed back being of such magnitude and phase in the output of said amplifier as to substantially cancel on said deflection plates the distortion produced by the presence of said coupling condensers.

2. The combination of claim 1 in which said wave-shaping network comprises a resistance-condenser combination.

3. The combination of claim 2 in which the capacitance of the condenser of said resistance-condenser combination is equal to or less than the capacitance of each of the said coupling condensers.

4. In a cathode ray beam deflection circuit of the electrostatic type, wherein the normal sawtooth voltage output of an amplifier tube as applied across a pair of cathode ray beam deflecting plates of a cathode ray tube is distorted by the use of a coupling condenser of relatively small capacity, the combination of a wave-shaping network connected to receive a portion of the normal sawtooth voltage output of said amplifier and to distort such voltage variation in a manner similar to the distortion produced by said coupling condenser, and a feed-back connection from the output of said wave-shaping network to the input of said amplifier tube.

5. In a device of the class described, the combination of an electrostatically deflected cathode ray tube, a pair of grid-controlled electron discharge tubes connected in "push-pull" relation and adapted to deliver substantially balanced voltages to two deflecting plates of said cathode ray tube, to deflect the cathode ray beam developed therein at a predetermined frequency, the anodes of said electron discharge tubes being respectively connected to the said deflecting plates through coupling condensers of small capacity resulting in a time constant which is inadequate for linear deflection of the beam at the predetermined frequency, a further condenser, a resistor, a circuit connecting the anode of one of said electron discharge tubes to a point of constant potential through the series combination of said further condenser and said resistor, and a connection from a point between said further condenser and said resistor to the grid of said one electron discharge tube.

6. The combination of claim 5 in which said further condenser and said resistor act in effect as a differentiating network.

7. The combination of claim 5 in which the capacitance of said further condenser is less than capacitance of any one of said coupling condensers.
